RIVET AND BURR

Franklin R. White, Waterbury, Conn., assignor
to The Patent Button Company, Waterbury,
Conn., a corporation of Connecticut

Application January 20, 1936, Serial No. 59,941

2 Claims. (Cl. 85—40)

My invention relates to new and useful improvements in rivets and burrs, and has for an object to especially provide a burr that will have a clean smooth cutting edge, so that if ever necessary to remove the same from the cloth, it will not tear the cloth and the hole, cut by the burr, will have sharp and clean edges.

A further object of the invention is to provide a burr, wherein the mouth, besides having a smooth non-jagged cutting edge, at the same time will be sufficiently flared to permit easy and accurate entrance of the rivet.

As is well known, these rivets and burrs are machine-attached, and although the machines are very accurate, it sometimes happens that the rivet will not be in absolute alignment with an opening in the burr. As the mouth of the burr is relatively small, there is a possibility of the rivet passing to one side of the same. Therefore, a flared hub and mouth (within certain limits) are to be desired.

A still further object of the invention is to turn back the edge of the metal at the mouth of the flared hub to not only make a sharper smoother cutting edge but also reinforce the flared mouth and thus provide a stronger hub to guide the rivet in its entrance into the burr.

Still another object of the invention is to combine in the one burr an exceptionally clean cutting edge and a flared mouth, the flared mouth being reinforced by turning the metal inwardly back on itself within the hub of the burr.

With these and other objects in view, the invention consists in certain new and novel features and combination of parts, as will be hereinafter more fully explained and pointed out in the claims.

Referring now to the drawing showing a preferred embodiment,

Fig. 1 is an enlarged top plan view of a fragmentary portion of cloth with the burr and rivet attached thereto;

Fig. 2 is an enlarged sectional view taken on the line 2—2 of Fig. 1;

Fig. 3 is an enlarged fragmentary view, similar to Fig. 1, of a piece of cloth with the burr removed, showing the substantially sharp-cut hole formed during the attachment of the burr;

Fig. 4 is an enlarged sectional view of the burr and a side elevation of the rivet, showing them in an attaching position;

Fig. 5 is an enlarged plan view of the disk from which the burr is formed;

Fig. 6 is an elevational view of the same;

Fig. 7 is a view similar to Fig. 5 but with the burr being partly drawn into shape;

Fig. 8 is a sectional view thereof;

Fig. 9 is a view similar to Fig. 5, but with a further step in the formation of the burr;

Fig. 10 is a sectional view of the same;

Fig. 11 is a view similar to Fig. 5 showing the next to the last step in the formation of the burr;

Fig. 12 is a sectional view thereof;

Fig. 13 is a view similar to Fig. 5 with the burr in its completed form, the edge of the mouth being now turned back within the hub;

Fig. 14 is a sectional view thereof;

Fig. 15 is a bottom plan view of the completed burr.

At the outset, it might be mentioned that it is desirable in the formation of burrs that the mouth or end of the hub of the burr be relatively sharp, as if this is not so and the burr is wrongly placed and has to be removed, the rough or broken edge of the burr often, in its removal, catches in the threads and makes a torn or, what might be termed, a rough hole in the garment, which will cause it to be classed as a second. However, if the burr can be so made that the edges are relatively sharp and can cut a clean hole in the garment, a small misplaced hole will not be noticeable and the garment will pass inspection.

I have found, therefore, that if the burr has a flared mouth and the ordinary rough edge is turned inwardly of the hub and back on itself, the cutting edge will be relatively sharp and produce a clean-cut hole when attached.

These burrs are generally formed of copper and unless the edge is turned back, the cutting edge is likely to be dull and ragged.

Referring now more generally to the several views, and for the moment to Fig. 5, there is shown on an enlarged scale a disk 1 of copper, which is first subjected to proper dies, so that the disk will then take the shape as shown in Fig. 7, that is, the metal will be flowed to form a downwardly extending incomplete hub 2.

The partly formed blank is now subjected to still further dies (not shown), so that the blank will have the appearance shown in Fig. 9, that is, the central portion of the disk (the hub) has been further elongated, as may be seen at 3. The rim 4 is still retained and, as yet, there is no mouth in the hub.

This partly formed blank is then subjected to further dies (not shown), so that there is now the open mouth 5 at the end of the hub, and the said hub is slightly inwardly flared about centrally of its length, as at 6, while the portion 55

just adjacent the mouth 5, such as at 7, will extend slightly inwardly, as may be seen in Fig. 12.

The burr is then subjected to the final dies 5 (not shown), so that the edge forming the mouth 5 is now turned inwardly and back on itself within the mouth, as may be seen at 8 (Fig. 14) and at the same time, the mouth is flared slightly outwardly, as may be seen at 9.

10 A construction of this kind has three distinct advantages. First, by making the mouth as wide as possible, there is a better chance of the prong 10^a of the rivet 10 registering with the hub of the burr while being attached.

15 In the second place, by turning the ragged edge of the metal back, inwardly on itself, as at 8, there is now provided a smooth cutting edge at the mouth of the burr, which is not possible to obtain unless this metal is turned back as 20 described.

In the third place, the mouth of the burr is strengthened, so that as the prong 10^a is driven up into the mouth of the rivet and into the hub, it will form a better and stronger guide for the 25 rivet.

It will be understood that in most attaching machines, the burr is positioned over the cloth and the tack or rivet is fed to pierce the under surface of the cloth, as shown in Fig. 2. In this 30 figure, I have shown the cloth 11, the rivet driven up into the hub of the burr and mutilated or deformed by a plunger (not shown) to tightly fasten the burr with respect to the rivet.

It will also be understood that the mouth of 35 the rivet must not be flared too much, as then when the pressure is applied to deform the rivet and to compress the rivet and burr in their tight relationship, the burr might break down and would then mutilate the cloth if and when 40 removed. In other words, the mouth should be flared to provide sufficient entrance for the insertion of the prong of the rivet but must not break down or lose its form when being attached.

45 As mentioned, by turning in the metal at the mouth, there are no fins or rough spots in the cutting edge but, on the other hand, there is a knifelike edge provided that will cut a relatively

clean hole in the material to which it is attached. Furthermore, if necessary to remove the burr in case of misplacement, there is no possibility of the mouth of the burr or the cutting edge tearing the threads of the fabric as it is removed from the garment.

It is to be remembered that there is considerable pressure used in forcing the burr through the cloth and deforming the prong 10^a in the attaching operation, and the stronger the burr, 10 the less chance of its being mutilated.

From the foregoing, it will be seen that by forming a burr with a slightly flared mouth and by turning back the metal at the mouth, not only is the mouth made large enough to provide 15 a better chance of entrance of the prong and not only is the burr strengthened, but a relatively clean hole is cut through the garment during the attaching operation and, if the burr is to be removed, the edges of the hole will remain in their clean-cut condition.

Having thus described my invention, what I claim as new and desire to secure by Letters Patent is:—

1. As an article of manufacture, a rivet and 25 burr, said burr formed of relatively soft thin metal including an upper plate and a central depending restricted hub, the mouth of the hub being flared outwardly and the metal at the mouth being turned inwardly and pressed back 30 against the wall of the hub and extending just over the edge forming a relatively smooth cutting edge, said rivet adapted to be forced into said burr and be deformed in the burr, the mouth of the hub being slightly larger than the 35 diameter of the base of the prong of the rivet.

2. A relatively soft thin metal burr comprising a circular disk having a central depending hub, the mouth of the hub being flared, the metal at the mouth being turned back inwardly extending 40 just over the edge to provide a clean cutting edge and the said cutting edge being compressed and sharp enough to cut the cloth during attachment of the burr, and a rivet adapted to be passed through the hub of the burr and be deformed at the top of the burr to hold the burr 45 with respect to the rivet.

FRANKLIN R. WHITE.
